US0D1011367S

(12) **United States Design Patent** (10) Patent No.: US D1,011,367 S
Stroier (45) Date of Patent: ** *Jan. 16, 2024

- (54) **DISPLAY SCREEN WITH GRAPHICAL USER INTERFACE FOR PRESENTING WEBSITE ANALYTICS**

(71) Applicant: **Siteimprove A/S**, Copenhagen (DK)

(72) Inventor: **Christoffer Lund Stroier**, Copenhagen (DK)

(73) Assignee: **Siteimprove A/S**, Copenhagen (DK)

(*) Notice: This patent is subject to a terminal disclaimer.

(**) Term: **15 Years**

Related U.S. Application Data

- (63) Continuation of application No. 29/771,363, filed on Feb. 22, 2021, which is a continuation of application No. 29/621,701, filed on Oct. 10, 2017, now Pat. No. Des. 911,352.

CLAIM

The ornamental design for a display screen with graphical user interface for presenting website analytics, as shown and described.

DESCRIPTION

The FIGURE is a front view of a display screen with a graphical user interface for presenting website analytics. The broken lines showing a display screen and elements of the graphical user interface illustrate portions of the article, and form no part of the claimed design. The graph in the lower left corner is presented with broken lines and forms no part of the claimed design. The thick circular broken line presented with broken lines forms no part of the claimed design.
